UNITED STATES PATENT OFFICE.

HENRY WILLIAM GODFREY, CHARLES FREDERICK LEAKE, AND CHARLES EDWARD LUCAS, OF STAINES, COUNTY OF MIDDLESEX, ENGLAND.

MANUFACTURE OF LINOLEUM.

SPECIFICATION forming part of Letters Patent No. 425,875, dated April 15, 1890.

Application filed January 11, 1890. Serial No. 336,622. (No model.)

To all whom it may concern:

Be it known that we, HENRY WILLIAM GODFREY, engineer; CHARLES FREDERICK LEAKE, engineer, and CHARLES EDWARD LUCAS, linoleum manufacturer, subjects of the Queen of Great Britain, all residing at the Linoleum Manufacturing Works, Staines, in the county of Middlesex, England, have invented certain new and useful Improvements to in the Manufacture of Linoleum and like Fabrics, of which the following is a specification.

This invention has for its object improvements in the manufacture of linoleum and like fabrics with the pattern inlaid, the color extending through the thickness of the fabric. For this purpose we prepare tesserae of the various colors and arrange them in order, and lay them also one over the other, so as to form a block on the surface of which a section of the pattern appears. We transfer these tesserae layer by layer to the surface of a prepared backing or fabric. They are pushed forward by a reciprocating pusher. The fabric, with the tesserae upon it, passes beneath a segmental roller, which rolls over and consolidates the whole.

The process is as follows: We take the usual linoleum composition, which is chiefly composed of oxidized linseed-oil, resin, kauri gum, and cork, together with suitable coloring-matters; or wood-dust may be used to take the place of cork-dust, either wholly or in part. We mix and prepare it in various colors. We pass each color separately through calender-rolls and press it into a sheet, but without the usual canvas backing. It is then passed through a pair of rolls thinly coated with paraffine-wax, which it receives to prevent subsequent sticking. It is then fed through a cutting or stamping machine, which may consist of vertical cutters or punches suitably arranged and worked by cams. The cutters have funnel-shaped continuations to retain the tesserae as they pass through the cutters. They are long enough to contain a convenient number of tesserae in order one above another. These receivers have each an

opening or slit up one side to facilitate the removal of the tesserae. Having cut the figures of desired shape to the design or pattern, we set them as they come from the cutters into a block, each figure in its proper place, so that the block is formed of strata of loose figures, each stratum being a section of the design. From this block the prepared tesserae are passed onto a suitable backing of canvas or prepared linoleum and through a press. The press is steam or water heated.

As a press we use a sector of a large roll, and through its center is fixed a shaft with projecting ends, on which are fitted friction-rolls that move in paths formed in the framing. The sector is actuated by the reciprocating motion of a crank and connecting-rod, and is made to roll with a to-and-fro motion upon the flat bed-plate or the material which is interposed. At each corner of the sector is a strong projecting tooth, which engages a corresponding notch at the projecting corners of the bed-plate. The object of these teeth will be seen hereinafter. The center of the sector moves in a horizontal line and parallel with the bed-plate so far as coincides with the length of the material to be pressed at each stroke. At this point the teeth engage their respective notches. The center is carried on in an upward curve, and the teeth become the centers upon which the press hinges, and the sector is thus raised clear of the bed-plate. Upon the return-stroke of the crank the press again falls into contact with the material and rolls over it. The same thing occurs at the other end of the stroke. The object of thus raising the press at either end is to admit of the fabric being drawn forward. The sector is held and guided in its motion by a pair of side frames, and on each of these is a strong bracket for the purpose of carrying the shafts and gearing. At the extremity of these is fixed the plumber-block for carrying the crank-shaft. At a convenient distance, and in a line parallel with the center of the sector or press, upon each end of the shaft, is keyed a disk-crank. Each disk is cogged at its periphery, and is recessed on the inside to

form a double cam. These cams, while the press is raised upon its hinge, actuate drawing-out rollers which carry the fabric forward, and also a slide-plate which forces the layers 5 of loose tesserae toward the press. It should here be mentioned that the said block of tesserae is set upon a rising plate or platform, which is made to rise step by step, each step being exactly the thickness of the tesserae. A 10 second shaft, which gives motion to the crank-shaft, and which is geared to it, carries at either end a cam. These, through levers and connecting-rods, work a ratchet device which, through bevel-wheels and a transverse shaft 15 by which they are connected, operate the lifting-screws at the moment the propelling-slide is withdrawn, and so raises the block of tesserae that the next stroke of the slide pushes forward the uppermost layer.

20 In order that our said invention may be fully understood and readily carried into effect, we will proceed to describe the drawings hereunto annexed.

Figure 1 is an elevation, and Fig. 2 is a 25 plan, of a machine for the manufacture of linoleum in accordance with our invention.

A is the bed and table of the machine. Preferably it is cast hollow, and steam can be admitted to its interior.

30 B B are two standards upon the frame, and C C are bracketed arms projecting out from the standards. These arms carry a shaft D, which is driven in any convenient manner, and on this shaft are pinions gearing with 35 teeth formed upon wheels or disks E', mounted on the shaft E, and these wheels or disks gear with teeth upon other wheels or disks F' F', mounted upon a shaft F.

G is a segment of a large roller which rolls 40 to and fro upon the table A. It is mounted on a shaft H. The shaft is held in elongated holes or guide-passages formed in the standards B.

G' is a counterpoise formed in one piece 45 with the roller-segment G.

The shaft H is moved to and fro by means of connecting-rods I I, which pass to crank-pins upon the disks F' F'.

G* G* are teeth or projections at the 50 corners of the segmental roller G.

A* A* are cavities formed in the bed A to receive these teeth or projections.

K is a roller on which is wound a fabric suitable to form the backing of the linoleum. 55 This fabric may be prepared on the surface with a linoleum cement before it is brought to the machine.

L is another roller, on which the linoleum is wound as it comes out of the machine. The 60 fabric from the roller K is led up over a small guide-roll K' and over the surface of the table A, thence over another guide-roll K², and down and around the under side of the roller M. The surface of this roller is roughened to prevent it slipping upon the 65

fabric. The linoleum, after leaving the roller M, passes up over another guide-roll K³, and so it reaches the roller L, on which it is wound. On the shaft of the roller M there is a ratchet-wheel M', and a lever M² can turn 70 about the same shaft. This lever carries a pawl m, engaging with the ratchet-teeth, and it receives motion by means of a connecting-rod N, passing up to a lever O, having its fulcrum at O', and at its farther end carrying a roller O², which is held in a cam path f, formed upon the disk F'. This ratchet-gear may be provided upon one or upon both sides 75 of the machine.

P is a rising table. It has lugs p at its 80 ends, in which are screw-threads, and these engage with screws Q Q, having beveled pinions P' at their upper ends. These pinions engage with other similar pinions P² upon a horizontal shaft R, on which there is also a 85 ratchet-wheel R' and a lever R², carrying a pawl r, engaged with the teeth of the ratchet.

S is a connecting-rod passing from the outer end of the lever R² to the lower end of the lever T, which has its fulcrum at T', and at 90 T² carries a small roller held in a cam-path formed upon the disk E'. This ratchet-gear may be provided on both sides of the machine. By it, as will be seen, the ratchet-wheels R' are turned step by step as the cam 95 wheel or disk E' revolves, and the table P is gradually raised step by step, each step corresponding to the thickness of a sheet of tesserae.

U is a block formed of layers of tesserae arranged according to the pattern, and the layers are piled up one upon another.

V is a reciprocating blade, which at each forward motion pushes off the uppermost row of tesserae onto the surface of the receiving 100 fabric as it passes over the roller K'. The blade V receives motion by means of connecting-rods W W, passing to arms W' W', which are fast with the levers M², turning upon the shaft of the roller M.

The action of the machine has been already 110 explained. The arranged tesserae are pushed forward, layer by layer, onto the prepared fabric, which, moving forward, takes them beneath the segmental roller. This rolls over 115 them, pressing them and the fabric between its face and the table A beneath. At the end of the rolling movement the surface of the segmental roller rises from the table, the fabric is drawn forward a step, and the rolling 120 operation is repeated, by these means the tesserae becoming firmly united to the fabric or supporting-surface.

What we claim is—

1. The process, substantially as described, 125 consisting in preparing a block of tesserae arranged in accordance with the pattern and laid one over the other, pushing forward such tesserae layer by layer onto a receiving-surface, advancing the said surface, with the tes- 130

seræ upon it, step by step through a press, and consolidating the whole by an intermittent pressure, as herein set forth.

2. The apparatus, substantially as described, 5 consisting of a rising table on which the block of arranged tesserae is placed, a reciprocating blade by which the tesserae are pushed forward layer by layer, rollers which carry forward a receiving fabric step by step, a table, 10 and a segmental roller which rolls to and fro

over the table and is lifted away from it at the end of each travel, as herein set forth.

HENRY WILLIAM GODFREY.
